United States Patent Office

Des. 205,468
Patented August 9, 1966

205,468

VENDING MACHINE FOR LAMINATING SHEET OR CARD-LIKE ARTICLES

Lyman D. Dunn, Chicago, and Stanley Gembicki, Des
Plaines, Ill., assignors to Marlan Company, Chicago,
Ill., a corporation of Illinois

Filed May 21, 1965, Ser. No. 85,402

Term of patent 14 years

(Cl. D52—3)

FIG. 4

FIGURE 1 is a front elevational view of our design for a vending machine for laminating sheet or card-like articles.

We claim:

The ornamental design for a vending machine for laminating sheet or card-like articles, as shown.
